UNITED STATES PATENT OFFICE.

CHARLES F. BRAND, OF PHILADELPHIA, PENNSYLVANIA, ASSIGNOR TO
PHILADELPHIA ARCHITECTURAL IRON COMPANY, OF SAME PLACE.

IMPROVEMENT IN FIRE-PROOF PARTITIONS.

Specification forming part of Letters Patent No. 144,501, dated November 11, 1873; application filed
October 31, 1873.

To all whom it may concern:

Be it known that I, CHARLES F. BRAND, of the city of Philadelphia and State of Pennsylvania, have invented certain Improvements in Partitions for Buildings, of which the following is a specification:

My invention relates to the combination of sheets of corrugated iron, which take the place of walls or frame-work as ordinarily used, and sheets of iron or other metal of suitable construction for holding the plastering, as herein-after described.

Figure 1 is a plan view of a section of a partition, the top plate E being removed. Fig. 2 is a front elevation of the same, a portion of the lathing-sheets being removed. Fig. 3, Sheet No. 2, is a vertical section at the line x x of Figs. 1 and 2. Fig. 4 is an isometrical view of one of the head-plates E.

Like letters in all the figures indicate the same parts.

In the place of wooden frame-work or walls of masonry, to which the laths are confined in the usual manner, I use corrugated sheets of iron A, to which I confine sheet-metal laths by means of clips, the corrugations of the sheets having a lateral extension equal to the desired thickness of the partition, as seen in Figs. 1 and 3.

I do not confine myself to any particular construction of the laths, but prefer making them in sheets B, as shown in the drawings, which are made of plain sheets of iron or other metal, so bent as to form grooves over their surfaces, the short receding angles a tending to hold the plastering securely against the

surface angles b of the sheets. These sheets I make by means of a machine constructed especially for the purpose. As it forms the subject of a distinct application, its peculiar construction is omitted in this.

There are clips C confined to the lath-sheets B by means of rivets D. Their free ends are passed through openings d of the corrugated sheets A, and bent down upon the same, as represented in the drawings, whereby the sheets A B are held very firmly together. Other means may be used for confining the sheets, if desirable. The corrugated sheets A are held securely at their top and bottom edges by means of plates E E, which have flanges e e, that come against the corrugations, as seen in Fig. 3. The plates E are fastened to the floor and ceiling, or timbers of the same, by means of screws or nails.

Partitions constructed in the manner represented have great lateral strength in proportion to the amount of material, and may be very expeditiously constructed.

I claim as my invention—

1. The combination of sheet-metal laths with corrugated sheets A to form partitions, the laths being confined by means of clips C or other suitable fastening, substantially as described.

2. The combination of the flanged plates E with the corrugated sheets A, substantially as and for the purpose set forth.

CHARLES F. BRAND.
